CLAIM

The ornamental design for a beverage container, as shown and described.

DESCRIPTION

FIG. 1 is a perspective view of a first embodiment of a beverage container showing my new design;
FIG. 2 is a front view thereof;
FIG. 3 is a rear view thereof;
FIG. 4 is a left side view thereof;
FIG. 5 is a right side view thereof;
FIG. 6 is a top view thereof;
FIG. 7 is a bottom view thereof;
FIG. 8 is a partially exploded perspective view thereof in a first operational mode with the lid of the beverage container removed;
FIG. 9 is a perspective view of a second embodiment of a beverage container;
FIG. 10 is a front view thereof;
FIG. 11 is a rear view thereof;
FIG. 12 is a left side view thereof;
FIG. 13 is a right side view thereof;
FIG. 14 is a top view thereof; and,
FIG. 15 is a bottom view thereof.

The broken lines in the drawings depict portions of the beverage container that form no part of the claimed design.
